UNITED STATES PATENT OFFICE.

HARRY G. WEBSTER, OF CHICAGO, ILLINOIS.

MULTICONTACT RELAY.

1,133,449.

Specification of Letters Patent.

Patented Mar. 30, 1915.

Original application filed April 11, 1912, Serial No. 690,148. Divided and this application filed November 6, 1914. Serial No. 870,613.

To all whom it may concern:

Be it known that I, HARRY G. WEBSTER, a citizen of the United States, residing at Chicago, in the county of Cook and State of Illinois, have invented certain new and useful Improvements in Multicontact Relays, of which the following is a specification.

The present invention relates to relays generally, and more particularly to relays for use in systems, such as telephone systems, in which a considerable number of electrical circuits are to be controlled by the operation of a single relay; this application being a division of my pending application 15 Serial No. 690,148, filed April 11, 1912.

The principal objects of the invention are to provide a relay of this class which, even though provided with a large number of contacts for the control of a plurality of circuits, shall have contact points readily accessible for inspection so arranged that sparking at contacts will not interfere with proper electrical engagement, and contact surfaces less liable to gather dust than in the ordinary type of relay, in a structure characterized by extreme compactness of assembly and simplicity of construction.

In carrying out my invention, I preferably employ stationary contact springs projecting side by side in fixed relation to an operating magnet, and cooperating relatively flexible moving contact members which make wiping electrical engagement with the projecting portions of the stationary contact springs.

The several features and advantages of my invention will be more fully understood upon reference to the following detailed description taken in connection with the accompanying drawing; and the scope of the invention will be particularly pointed out in the appended claims.

Referring to the drawing, Figure 1 is a side elevation of a relay constructed in accordance with my invention; Fig. 2 is a plan view of one of the flexible contact members 68 of Fig. 1; Fig. 3 is a plan view of the bank of stationary contact springs indicated at 58 in Fig. 1, and Fig. 4 is a section elevation on an enlarged scale of said contact bank, the section being taken on a plane indicated by the line 6—6 of Fig. 1.

Throughout these views, like characters refer to like parts.

Referring to Fig. 1, 10 designates the usual relay winding mounted upon a core 13 having the spool heads 11. The core upon which the winding is mounted terminates at one end in the pole face adjacent to the armature 38, and at the other end in a threaded extension 14 provided with a nut 41 for securing the magnetic angle frame 36 to the core. The right hand end of the core and the right hand end of the angle frame 36 constitute the polar extremities of the relay magnet. The armature 38 is of the usual angular form, and as here illustrated, is supported at the extremity of the angle frame 36 by pivots 39 between projecting ears 37. The extension 14 of the core extends through both the angle frame 36 and the mounting strip 40, the parts being held in position by the nut 41 or in any other suitable manner.

As here illustrated, a leaf spring 42 is secured to the rear end of the extension 43 of armature 38 and cooperates with an overhanging hook 44 secured to the frame 36 to return the armature 38 to normal.

A screw 45 threaded through the armature 38 and locked in place by a lock nut 46, provides for the adjustment of the air-gap between the armature and the pole face of the core 13.

In the invention as here illustrated, the fixed contact springs are in the form of metal strips 47, 48, 49, 50, 51, 52, 53, 54, 55 and 56, rigidly supported throughout their length and secured to the mounting strip 40 by angle plates 57, 58, connected by screws 59 extending through suitable insulating strips 60, 61, 62, 63, 64, 65 and 66, which insulate the contact strips from each other and from the screws and plates. The rear ends of these strips are provided with extensions 67 for the purpose of enabling soldered wire connections to be made thereto. By this construction, the free ends of these various contact springs are supported by the insulating strips 60, 62, 64 and 66, and thus the several pairs, as 53—55, are prevented from unduly spreading when engaged by a co-operating moving contact member. Obviously, the stationary contact

springs may be made of sufficient weight and stiffness to secure this result without extending the insulating strips 60, 62, 64 and 66 along side of the free ends of these springs.

5 To coöperate with the stationary contact springs, I provide a series of contact springs 68, positioned side by side, in edgewise relation to the magnet structure and collectively 10 forming a bank extending transversely thereto. As shown at Figs. 1 and 2, contact springs 68 are each provided with two flexible contacting ends 69 which are convexly curved so as to readily engage between co- 15 operating pairs of stationary contact springs and establish wiping engagement therewith. The moving contact springs 68 are secured at their non-contacting ends by an insulating mounting 70, which is connected in any 20 suitable manner, as by screw 71, with the extension 43 of armature 38. By this construction, the contact springs 68 are insulated from the other parts and from each other, and may be provided with circuit connections 25 at points 29, or may serve merely to bridge pairs of coöperating stationary contact springs.

It will be understood that in operation, the pulling up of the armature 38 will move 30 the flexible contacting ends 69, of the contact springs 68, out of engagement with the lower stationary contact springs, such as 48 and 49, and into engagement with the upper stationary contact springs such as 47 and 49, 35 the contact spring 49 extending opposite both contact springs 47 and 48. Upon retraction of the armature, contact springs 47—49 will be disengaged and contact springs 48—49 engaged.

40 It will be apparent that the stationary contact springs may be variously arranged, and that the contact ends of the moving contact springs 68 may be varied in width to suit the requirements of the coöperating 45 stationary contact springs, and that both may be varied according to the circuit requirements or judgment of the one employing the invention. As shown in Fig. 4, it will be seen that in the case of contact 50 springs 69, the circuit between contact springs 48 and 49 is broken before the circuit between 47 and 48 is closed. By making the flexible contacts broader, as illustrated at 72, the second circuit may be closed before 55 the first is opened, and vice versa. Or again, by replacing the wide spring, such as 49, by two narrow springs, such as 55 and 56, and providing relatively narrow flexible contacts 69, contact springs 68 may be connected 60 at point 26 to one of the circuit wires and will then serve to establish at one time a multiple connection to contact springs 54—56, and in the alternative position a multiple connection to the contact springs 53—55.

65 While I have indicated at Fig. 2 a particu-

lar form of flexible moving contact spring, it is to be understood that obviously the moving spring may be arranged in a variety of ways. It is not essential to my invention that the moving contact spring should enter between 70 to engage coöperating stationary springs, for obviously the ends of the moving contact spring might be arranged to engage with opposite sides of a single stationary spring. Obviously, also, the movable contact spring 75 68 might be provided with a single flexible end 69, or might be made of a single integral piece of flexible sheet metal. It will also be apparent that the invention here disclosed may be embodied in various other 80 alterations and modifications without departing from its spirit and scope. I therefore do not wish to be unduly limited, but aim to cover all such adaptations, alterations and modifications by the terms of the ap- 85 pended claims.

What I claim as new and desire to secure by Letters Patent of the United States is:—

1. A multi-contact relay comprising a magnet structure, an armature actuated thereby, an insulating mounting rigidly related to said magnet structure, a series of relatively rigid contact members carried at one end by said mounting and projecting therefrom side by side forming a bank, and 90 a series of relatively flexible contact members movable in planes intersecting the plane of said bank actuated responsive to movement of said armature to make wiping electrical engagement with the projecting portions of certain of said rigid contact members.

2. A multi-contact relay comprising an insulating mounting, a series of relatively rigid contact members supported by said 105 mounting and projecting therefrom side by side forming a bank, an armature, a magnet structure to actuate said armature presenting opposite polar extremities thereto, and a series of relatively flexible wiping contact members movable in planes intersecting the plane of said bank and actuated responsive to movement of said armature to electrically engage the projecting portions of certain of 110 said rigid contact members.

3. A relay structure comprising an electro-magnet, an angle frame, an angular armature actuated by said electro-magnet fulcrumed on said frame and having an extension lying in close proximity thereto, a 115 series of contact springs secured to the rear end of said frame and projecting forward toward said armature extension said contact springs being arranged side by side in a plane parallel to said electro-magnet, and a 120 series of flexible wiping contact pieces carried by said armature extension and movable under the action of said armature into and out of engagement with certain of said 125 contact members.

4. A multi-contact relay comprising an electro-magnet and a frame, an insulating mounting rigidly related thereto, a series of relatively rigid contact springs carried at 5 one end by said mounting and projecting therefrom side by side forming a bank, an armature actuated by said electro-magnet and fulcrumed on said frame, and a series of relatively flexible contact springs forming a 10 second bank co-extensive transversely with the first mentioned bank said springs individually being positioned in edgewise relation to said electro-magnet and actuated responsive to movement of said armature to engage certain of said rigid contact springs. 15
5. A multi-contact relay comprising a magnet structure, an armature actuated thereby, an insulating mounting rigidly related to said magnet structure, a series of 20 relatively rigid contact springs carried at one end by said mounting and projecting therefrom side by side forming a bank, and a series of pairs of flexible contact members movable in planes intersecting the plane of

said bank and actuated responsive to movement of said armature to make wiping electrical engagement with certain of said contact springs, the respective pieces of said pairs being oppositely flexed thereby to, equalize the thrust against said contact 30 springs.

6. A multi-contact switch comprising a magnet structure, an armature actuated thereby, a series of relatively rigid contact pieces supported in fixed relation to said magnet structure, and a series of relatively flexible contact members positioned in edge-wise relation to said magnet structure actuated responsive to movement of said armature to make wiping electrical engagement 40 with certain of said contact pieces.

In witness whereof, I hereunto subscribe my name this 4th day of Nov. 1914.

HARRY G. WEBSTER.
